UNITED STATES PATENT OFFICE.

LEVI M. RINKER, OF PITTSBURGH, PENNSYLVANIA.

PIPE-ORGAN STRUCTURE.

Application filed December 21, 1922. Serial No. 608,365.

To all whom it may concern:

Be it known that I, Levi M. RINKER, residing at Pittsburgh, in the county of Allegheny and State of Pennsylvania, a citizen of the United States, have invented or discovered certain new and useful Improvements in Pipe-Organ Structures, of which improvements the following is a specification.

My invention relates to improvements in pipe-organ structure and consists in means for arranging combinations of stops, which combinations, having been set up beforehand, may be brought alternately and repeatedly into service, as the player may desire.

In the accompanying drawings Fig. I is a view in plan and Fig. II a view in side elevation of apparatus embodying my present invention; Fig. III is a view in vertical section of a portion of this apparatus, the plane of section being indicated by the line III—III, Fig. I; Fig. IV is drawn to larger scale and illustrates in side elevation and in section a detail shown in Fig. III; Fig. V is a view in vertical section, on the plane indicated at V—V, Fig. I; Fig. VI is a view in vertical section, on a plane at right angles to that of Fig. V, on the plane indicated at VI—VI, Fig. V. It will be perceived that Figs. III and VI together afford a view in longitudinal section of the whole, though not in a single plane of section. Figs. VII, VIII, IX, and X are views, Fig. VII in horizontal section, Figs. VIII, IX, and X in vertical section, of a certain switch which forms an essential part of the invention. The planes of section of Figs. VII, VIII, IX, and X are indicated by correspondingly numbered section lines, each on another figure of this group, and will readily be understood. Fig. XI is a diagrammatic scheme of the electric wiring of the whole.

The apparatus as I have here illustrated it, is in some sense a model; it does not include the whole system of stops of a pipe organ, but only three. I have so far reduced the number of stops, in order to keep the showing simple. This showing being clearly comprehended, it will be manifest that to apply the invention to a complete system of stops, however large that system may be, is a mere matter of duplication of parts.

I show here three stops (or, to speak precisely, three stop controlling levers) and two combinations,—that is to say, means for set-

ting up beforehand two arrangements of these three stops, which arrangements being once set up, may alternately be brought into service, as the player may desire. It will further be perceived that an increase in the 60 number of combinations, beyond what is here shown, and to any desired extent, is a mere matter of duplication.

The apparatus is electrical; mechanical parts are swung by electro-magnets, energized from a suitable source, and switched in and out of service in proper coordination.

Dominating the whole is a switch adapted to be swung from one to another of two alternate positions. When in one position 70 the combinations may be set up. After the combinations are set up, this switch may be shifted to its alternate position; and then one or another of the already set-up combinations may be made effective, as desired. 75

Referring to Figs. I and II, A is the tablet board of the console of an organ; S are stop-controlling levers; C are combination buttons, and W are switch buttons. It is to be understood, first of all, that the stop levers 80 S may be individually swung and stops operated in usual manner. My invention does not disturb that condition of things. The organ may, accordingly, be used, without resort to my invention, the stops then being 85 individually operated. My invention comes into play and becomes valuable, when it comes to bringing into service all at once and through the pressing of a single button a particular prearranged combination of 90 stops.

The switch which has already been referred to is fully illustrated in Figs. VII—X, and will presently be described. Suffice it here to remark that by pressing 95 alternately one and the other of buttons W, this switch may be thrown from one to the other of its two operative positions. Let it be supposed that it has been thrown to the position preparatory to the setting-up of 100 stop combinations, the position which I shall hereafter designate as the setting-up position. When the switch has been swung to this position, and when in sequence thereafter one or more of stop levers S in desired 105 combination have been shifted, either one of buttons C may be pressed; and thereafter, the switch having meanwhile been swung to its alternate position, which hereafter I shall characterize as playing position, whenever 110

this same button C is pressed, stop levers S will be shifted in this particular combination.

Referring particularly to Figs. I, III, and 5 IV, a series of bars 1 will be remarked, mounted in suitable ways and adapted to be shifted longitudinally. Each bar carries a series of pivotally mounted contact pieces 2. One such bar is provided for each stop lever, 10 and, accordingly, as I here show three stop levers S and no more, three bars 1 are present. Each bar carries a contact piece for each combination button, and since for present purposes I show two combination buttons C, each bar 1 here carries two contact pieces 2.

The bars 1 are arranged side by side in parallelism. At one end, the right-hand end, as seen in Figs. I and III, each bar is 20 provided with a push rod 3 pivoted to it. These push rods are formed of soft iron and are subject each to the influence of one of the three electromagnets 4, of which further mention will presently be made. At opposite ends of the series of bars 1 with their push rods 3 are arranged transverse rods 5 and 6 mounted to be shifted in the general plane in which the bars extend and in a direction longitudinally of the bars. A spring 30 7 engaging rod 5 tends always to hold the bars at one end (the right-hand end) of their range of longitudinal sliding. A spring 7^a engaging rod 6 tends always to hold it at the right-hand limit of its range 35 of swinging. An electro-magnet 8 when energized drives actuating rod 6 to the left against the tension of spring 7^a and, engaging one or more of push rods 3, carries the corresponding bars 1 to the left against 40 the tension of spring 7. If one or more of magnets 4 be energized before the energizing of magnet 8, the corresponding push rods 3 will be drawn upward, out of the pathway of rod 6, and consequently when magnet 8 45 is energized and rod 6 shifted, the bars 1 whose push rods 3 have so been drawn aside will not be carried from right to left, as otherwise they would be.

Extending transversely beneath bars 1 50 are rods 9 mounted to be shifted transversely of their extent, that is to say toward and from the contact pieces, presently to be described, carried by bars 1. The rods 9 correspond in number to combination buttons C (and to sets of contact pieces 2), one for 55 each button. The desired movement may conveniently be achieved by forming them as bends in rotatably mounted lengths of wire, after the manner clearly shown in Figs. I and III. Each of these lengths of wire is 60 prolonged at one end to form a crank arm 10, and each crank arm 10 is linked to contact-shifting bar 40, and each bar 40 is linked in turn to a soft iron push rod 11. The bars 40 lie side by side and in paral-

lism with the bars 1, and like the bars 1 are shiftable longitudinally, from right to left, as seen in Fig. I. The push rods 11 (two in number, because no more than two combination buttons C are shown) extend 70 adjacent to and in approximate parallelism with and in approximately common plane with push rods 3 already described. Associated with each push rod 11 is an electromagnet 12. It has been explained, concerning push rods 3, that when any of the magnets 4 is energized the corresponding push rod is drawn aside, out of the pathway of the swinging transverse rod 6. It is to be remarked concerning push rods 11 that, 75 while they extend approximately in common plane with push rods 3, they lie normally out of the pathway of the swinging rod 6, and that when magnets 12 or any of them are energized the corresponding push rods 11 80 will be drawn into the pathway of swinging rod 6.

The push rods 3 and 11 are alike in this, that normally they rest by gravity in their 90 lower position, that they are raised by the magnets 4 and 12, and that when a magnet is deenergized the corresponding rod swings by gravity to its initial position.

The transverse rod 5, swinging, carries 95 bars 1 from left to right (Fig. III), and carries with the bars the push rods 3; the swinging of rod 5 has no effect, to shift rods 9 nor to return bars 40 from left to right.

When the switch is in playing position 100 any one of the stop levers S may be independently swung, but the independent swinging of the stop lever under the conditions indicated will have no effect upon the electrically controlled apparatus which I 105 here am describing.

When the switch is in setting-up position, however, the shifting of a stop lever will 110 effect the energizing of a magnet 4. There are as many bars 1 as there are stops, and as many magnets 4 as there are stops; each magnet 4 is, under the conditions indicated, under control of one of the stop levers. Accordingly, when the switch stands in setting-up position, the shifting of a stop lever 115 energizing the corresponding magnet, raises the corresponding push rod 3 out of the path of swing of transverse rod 6.

When the switch is in setting-up position, the pressing of either combination button C 120 energizes simultaneously one of the electromagnets 12 and also an electromagnet 30. The energizing of an electromagnet 12 raises the corresponding push rod 11 into the path of swing of transverse rod 6; the energizing of 125 electromagnet 30 swings a spring-restrained rod 31 composed wholly or superficially of soft iron (in fact it is made of iron surfaced phosphor bronze) and closes an electric circuit which circuit, being closed, energizes a second electromagnet 13. When 130

electromagnet 13 is energized it raises against spring tension (or gravity) its armature 14, and in so doing closes another circuit. This circuit, being closed, energizes electromagnet 8. Thereupon the armature 15 of magnet 8 is attracted and drawn, against the resistance of springs 7 and 7^a with the result that transverse rod 6 is swung. By the swinging of rod 6 those bars 1 are shifted from right to left (Figs. I, III) whose push rods 3 have not been drawn aside by electromagnets 4, and those bars 40 are shifted whose push rods 11 have been drawn aside by magnets 12. The shifting of a bar 40 effects the swinging of the corresponding rod 9.

The reason for the step-up or relay of energizing current through the successive magnets 30, 13, and 8, is to delay the swinging 20 of transverse rod 6 until the push rods 3 and 11 shall surely have been swung selectively and come to position desired before rod 6 advances.

Each bar 1 carries as many contact pieces 2 as there are combination buttons C. Each line of contact pieces 2 borne by the plurality of bars 1 is arranged adjacent the path of swing of one of the transverse rods 9. The swinging of either rod 9 will effect 30 the swing from inactive to active position of the corresponding contact pieces 2 upon so many of bars 1 as have not been driven from right to left by the swinging of rod 6,—those bars 1 whose push rods 3 have 35 by the energizing of their magnets 4 been drawn aside from the path of rod 6.

Fig. XI shows all the contact pieces 2 but one in inoperative position; and uppermost on the left, as there shown, is in operative position. Fig. IV shows the contact piece in detail, and indicates how it is pivoted to bar 1. The contact piece may be provided with a boss 2^a, and the bar may be provided with suitably placed recesses or 45 perforations 1^a, to the end that (the body of the contact piece being itself somewhat resilient), the contact piece will be held with sufficient security first in one and then in the other of its alternate, operative and inoperative positions. The swinging bar 9 engages the properly disposed surface 2^b, to effect turning of the contact piece from inoperative to operative position.

The sequence of movements in the setting 55 up operation is this: (1) The switch (presently to be described) is brought to setting-up position; (2) such ones of stop levers S as are to be brought into combination are swung. Thereupon the corresponding electromagnets 4 are energized and the push rods 3 of the corresponding bars 1 are raised out of the path of rod 6. (3) One of the combination buttons C then is pressed. The corresponding electromagnet 60 12 is energized, and the corresponding push

rod 11 is drawn into the path of rod 6. With a short and sufficient delay, but by this same pressing of button C, the sequence of electromagnets 30, 13, and 8 is energized, and transverse rod 6 is swung. The swinging 70 of rod 6 effects the shifting out of the way of so many of bars 1 as are not to serve in setting up the particular combination, and also the swinging of the appropriate rod 9. The swinging of this rod 9 75 effects the shifting of the corresponding contact pieces 2 upon those bars 1 which have remained stationary and have therefore become participants in establishing the particular combination. 80

It is the shifting selectively of certain of the aligned contact pieces 2 on the series of bars 1 which establishes the combination. As shown in the drawings it is the right-hand line of contact pieces 2, on bars 1, Fig. I which is coordinated with the upper combination button C, and the left-hand line which is coordinated with the lower button. 85

When a combination in one row has been set up in the manner described, a new combination of stop levers may be swung and then the other button C pressed, and this second combination by duplicate instrumentalities will then be imposed on the second row of contact pieces 2. 90 95

The keys have now been fashioned (so to speak) by which either combination may be unlocked (that is, brought into operation) at will.

As I have said, the number of rows of 100 contact pieces 2, the number of combination buttons C, and the number of sets of interconnected operating instrumentalities may be increased indefinitely.

It may be noted in passing that when, 105 while the switch remains in setting-up position, the stop levers previously swung are swung back to normal (whereby the corresponding electromagnets 4 are deenergized), the subsequent pressing again of a combination button previously pressed (effecting as it does the simultaneous swinging of bar 6 and of the proper one of loops 9) will effect the swinging back to inoperative position of contact pieces 2 previously swung to operative position in that particular combination. This is effected by engagement of loop 9 with properly disposed surfaces 2^c 110 of the contact pieces of the receding bars 1. 115

Having now explained how combinations are set up by a selective swinging of contact pieces 2 upon bars 1, it remains to explain how, when the switch has been shifted to playing position, the pressing of either combination button C will effect the swinging of stop levers S, in the previously set up combination. 120 125

Adjacent and extending transversely above bars 1 are swinging rods 16, one for each set of contact pieces 2,—one for each 130

- combination button C. Electromagnets 17 are provided, one for each combination button C. Each electromagnet 17 has a soft iron spring-backed (or weighted) armature, 5 which alternately rises and falls as the electromagnet is energized and deenergized, and in rising and falling the armature effects the swinging of the corresponding rod 16. Normally the rods 16 extend in positions 10 remote from contact pieces 2; but when, on the pressing of either combination button C (the switch standing in playing position), the corresponding electromagnet 17 is energized, the corresponding rod 16 will be 15 swung, and electric circuit will be closed through so many of contact pieces 2 as have previously been shifted (after the manner already described) from inoperative to operative position.
- 20 For each stop lever S is provided a shift rod 18 (Figs. V and VI). These shift rods are formed of soft iron. They extend substantially vertically downward and terminate with their lower ends in horizontal 25 alignment. These lower ends are turned or hooked as indicated at 18^a. Opposite the free end of each rod 18 is arranged an electromagnet 22 adapted when energized to draw its particular rod 18 against gravity 30 (augmented if need be by spring resistance) into the pathway in which a transverse rod presently to be described swings. The contacts made by the swinging of one of rods 16 will close circuits which energize such 35 ones of electromagnets 22 as correspond to the operative contact pieces 2, and, accordingly, certain of rods 18 will be swung to accomplish the end indicated.
- When (the switch being in playing position) one of the combination buttons C is 40 pressed, not only will one of the electromagnets 17 be energized (with the ensuing operations already described); electromagnet 30, already described as serving in the setting-up operation, will also and simultaneously be energized. The magnet 30 being energized will draw rod 31 to itself as before, and as before will close a circuit; but the 45 circuit now closed will, in consequence of the shifting of the switch, no longer energize electromagnet 13, but instead it will energize another electromagnet 23, and this other electromagnet, by drawing to itself a spring-resisting (or gravity resisting) soft 50 iron armature, will close another circuit and energize another electromagnet 21. Precisely as before, and through two step-up or relay actions electromagnet 21 will be energized by the pressing of either combination 55 button C, but only at a substantial and sufficient interval after the energizing of one of the electromagnets 17, and also (and this too is important) at a sufficient interval after the energizing of so many of electromagnets 22 as the particular combina- 60 tion requires. There is one step-up from pressing button C to energizing electromagnets 22; there are two steps-up, from pressing button C to energizing electromagnet 21. The difference of one step affords the desired 70 time interval for push rods 18 to come to place before the transverse rod swings to drive them.
- The transverse rod 19, repeatedly alluded to above, swings in response to the energizing of magnet 21 against the tension of a spring 20 in a vertical path upward and in so doing engages and drives upward so many of push rods 18 as have previously been drawn by their electromagnets 22 into the 75 pathway of rod 19. This driving of rods 18 upward swings the stop levers with which they severally are connected.
- Simultaneously with the upward swing of rod 19, the energizing of magnet 21 effects 80 also the downward swing (against the same spring tension) of a second rod 32. This rod 32, so swinging downward, engages the hooked ends 18^a of so many of rods 18 as may then stand unresponsive to magnets 22 85 but still in elevated position, and draws them downward, and swings the stop levers with which they are connected to inactive position. Thus the simultaneous swinging of rods 19 and 32, one upward the other 90 downward, insures the desired setting of the stops. Incidentally the rod 32 may have a wing-like extension 32^a to ensure the continued abutment of the rising rod 19 against the ends of rods 18. The rods 19 and 32 100 swing under tension of spring 20 when magnet 21 is deenergized to allow push rods 18 to swing to inactive position. A bellows 33 cushions the thrust of the armature of magnet 21.
- Magnet 21 is deenergized immediately after action, on the release of the previously pressed button C. The stop-levers remain in the positions to which they have been brought, and the combination may then be 110 modified by the player, by swinging the stop levers S individually, as he may desire.
- Without further elaboration, it will now be understood that, the desired combinations having been set up, by imposing on the rows of contact pieces 2 particular arrangements, and the switch having been shifted from setting-up to playing position, with the pressing of a button C stop levers S will be swung in the predetermined combination, one button C after another may be pressed and the several predetermined combinations made effective; and the same combination may be made effective again and again, whenever the particular button which controls that combination is pressed.
- When previously set-up combinations are to be destroyed, all that need be done is to shift the switch to setting-up position and, 120 all the stop levers being in inactive position,

to press the combination buttons C. The rods 9 then will swing and, all the bars 1 being driven back, all the previously swung contact pieces 2 will by engagement with 5 rods 9 be returned from operative to inoperative positions.

In summary of electromagnet energizing, magnets 4 are energized only when the switch stands in setting-up position, and are 10 energized by the swinging of stop levers S; magnets 12 are energized only when the switch stands in setting-up position and are energized by the pressing of the combination button C; magnets 17 are energized only 15 when the switch stands in playing position, and are energized only by pressing combination buttons C; and magnet 30 is energized by the pressing of either button C, whether the switch stand in setting-up or in playing 20 position. If the switch stands in setting-up position, energizing of magnet 30 effects sequent energizing of magnet 13, and through it of magnet 8; if the switch stands in playing position, energizing of magnet 25 30 effects sequent energizing of magnet 23, and through it of magnet 21. If the switch stands in playing position, energizing of one of magnets 17 effects the sequent selective energizing of magnets 22.

30 Referring to Figs. VII-X the switch structure will readily be understood in principle. The switch includes a rotary block 24, and operative connections, whereby the pressing of first one and then the other of 35 buttons W will bring it to one or the other of its alternate positions. One of these positions is that previously characterized as the setting-up position; the other, playing position.

40 The block 24 is equipped with opposite series of contact pins 25. When in one of the two alternate positions, one series of pins closes circuit through a series of leads, 26—27; when in the opposite position the 45 other series of pins closes circuit through another set of leads, 28—29.

In the diagrammatic showing, Fig. XI, a 50 source of electric energy is indicated at 34. This may be understood to be a generator of, say, 10 amperes at 10 volts. In this figure leads 35, 36 are shown; and these, it 55 will be understood are leads through which the actual shifting of stops is effected—the stops in the organ, as distinguished from the stop levers. According as the stop levers S are depressed the electric circuit is closed through lead 35 and one of leads 36, to 60 actually accomplish stop shifting in the organ.

60 In Fig. XI the switch is shown to be in setting-up position and all the other manually controlled contacts open. If now one of stop levers S be depressed, contact will be 65 made at a, and an energizing current, completed through the switch, will flow through

a magnet 4. One of push rods 3 will then be raised, out of the path of swing of transverse rod 6. When thereafter a combination button C is pressed, contact will be made at b, and one of magnets 12 and magnet 30 70 will be energized, circuit being completed through the switch. The energizing of a magnet 12 will cause a push rod 11 to be drawn into the path of swing of transverse rod 6; the energizing of magnet 30 will cause 75 armature 31 to be drawn to it and contact will be made at c. The closing of contact c will effect energizing (through the switch) of magnet 13. When magnet 13 is energized, it will draw its armature to itself and make contact at d. When contact d is closed, magnet 8 will be energized and bar 6 swung. The swinging of bar 6 will by the instrumentalities described and under the conditions already brought about effect the desired selective swinging of contact pieces 2.

80 After these operations have been performed the switch may be swung to playing position. Then, if one of the combination keys C be pressed, one of magnets 17 will 85 be energized, the current being completed through the switch, and magnet 30 will simultaneously be energized again. The energizing of a magnet 17 will effect the 90 swinging of a transverse rod 16 and a consequent contact or contacts with contact pieces 2, previously arranged. The making of contact between a rod 16 and a contact piece 2 will close, through the switch, a circuit through one of magnets 22, energizing 95 it; thereby one of rods 18 will be swung into the pathway of swinging rod 19. The energizing of magnet 30, closing again contact at c, will now cause an energizing current 100 (completed through the switch) to flow through magnet 23; this will effect a making of contact at e; and thereupon an energizing current will flow through magnet 21. This will effect the swing of rod 19, upward thrust of rod 18 and depression of stop 105 lever S, setting up the desired flow of current through lead 35 and the corresponding lead 36.

110 I have shown stop levers, and have shown swinging members S which are properly so termed. Manifestly, it is a mere matter of mechanical adaptation to apply my invention to an organ structure in which the stops are operated by draw knobs instead of levers. In the ensuing claims I shall use the generic term stop member, to include such alternate devices.

115 The advantages of the structure which now I have described are, first, simplicity, and economy of space; second, while the rods 18 and their immediately associated parts, and the electromagnet 30 with its armature are mounted on the tablet board, the setting-up bars 1 with their immediately associated parts and the remainder of the or- 120 125 130

gan operating apparatus as well may be located where one will, quite independently of the position of the console. The console itself, therefore, may be made small, and will accommodate itself more easily to extraneous conditions. Third, the apparatus which I have shown and described may be energized from the electric generator provided to operate the organ. And, finally, in connection with the advantages enumerated, a combination once set up may be brought into service again and again; the service of the apparatus is not exhausted with one operation.

15 I claim as my invention:

1. In mechanism for controlling the stops of a pipe organ the combination of a plurality of stop members, a combination control member, a plurality of longitudinally movable contact-carrier bars, corresponding in number to the stop members, and arranged in parallelism, side by side, a contact-shifting bar arranged in parallelism, side by side, with the contact-carrier bars and movable alternately to active and inactive position, contact-shifting means adapted to be moved by the longitudinal traverse of the said contact-shifting bar and in movement to engage and shift the contact pieces borne by said contact-carrier bars, a bar-shifting rod extending transversely, opposite the aligned ends of all of said bars and movable in the direction of the length of said bars, a plurality of thrust transmitting devices one for each of said contact-carrier bars, each movable from normal operative position between the said rod and that contact-carrier bar with which it is associated, means operated by the movement of each stop member for moving from operative position the thrust-transmitting device of the corresponding contact-carrier bar, a thrust-transmitting device movable from normal inoperative position to thrust-transmitting position between said rod and said contact-shifting bar, means operated by the movement of said combination control member for effecting two sequent movements: first, movement to operative position of the thrust-transmitting device last mentioned, and, second, movement of the bar-shifting rod, the parts being so proportioned that movement of the contact-shifting means aforesaid by the longitudinal traverse of said contact-shifting bar tends to swing to active position the contact pieces upon those contact-carrier bars which remain in normal position and to swing to inactive position the contact pieces upon those contact-carrier bars which have been shifted by the bar-shifting rod.

20 2. In mechanism for controlling the stops of a pipe organ, the combination of a set of stop members, longitudinally shiftable push rods, each engaging one of said stop members, a second set of movable bars corresponding in number to said stop members, a plurality of combination-control members, each of the bars of said second set provided with a plurality of swinging contact pieces corresponding in number with said combination-control members, a switch movable from one to the other of alternate setting-up and playing positions, means operative on movement of said combination-control members when the switch stands in setting-up position for shifting selectively said contact pieces, and means operative on movement of said combination-control member when the switch stands in playing position for energizing circuits through such previously shifted contact pieces thereby shifting selectively the push rods first named.

25 3. In mechanism for controlling the stops of a pipe organ the combination of a plurality of stop members, a combination control member, a plurality of longitudinally movable contact-carrier bars, corresponding in number to the stop members, and arranged in parallelism, side by side, and movable against yielding resistance from normal position, a contact-shifting bar arranged in parallelism, side by side, with the contact-carrier bars and movable longitudinally from normal inactive position, a contact piece borne pivotally by each of said con-

tact-carrier bars and movable alternately to active and inactive position, contact-shifting means adapted to be moved by the longitudinal traverse of the said contact-shifting bar from normal position and in movement to engage and shift the contact pieces borne by said contact-carrier bars, a rod extending transversely, opposite the aligned ends of all of said bars and movable in the direction of the length of said bars and adapted in movement to shift said bars from normal position, a plurality of thrust-transmitting devices, one for each of said contact-carrier bars, each movable from normal operative position between the said rod and that contact-carrier bar with which it is associated, means operated by the movement of each stop member for moving from operative position the thrust-transmitting device of the corresponding contact-carrier bar, a thrust-transmitting device movable from normal inoperative position to thrust-transmitting position between said rod and said contact-shifting bar, means operated by the movement of said combination control member for effecting two sequent movements: first, movement to operative position of the thrust-transmitting device last mentioned, and, second, movement of the bar-shifting rod, the parts being so proportioned that movement of the contact-shifting means aforesaid by the longitudinal traverse of said contact-shifting bar tends to swing to active position the contact pieces upon those contact-carrier bars which remain in normal position and to swing to inactive position the contact pieces upon those contact-carrier bars which have been shifted by the bar-shifting rod.

30 4. In mechanism for controlling the stops of a pipe organ, the combination of a set of stop members, longitudinally shiftable push rods, each engaging one of said stop members, a second set of movable bars corresponding in number to said stop members, a plurality of combination-control members, each of the bars of said second set provided with a plurality of swinging contact pieces corresponding in number with said combination-control members, a switch movable from one to the other of alternate setting-up and playing positions, means operative on movement of said combination-control members when the switch stands in setting-up position for shifting selectively said contact pieces, and means operative on movement of said combination-control member when the switch stands in playing position for energizing circuits through such previously shifted contact pieces thereby shifting selectively the push rods first named.

35 5. In mechanism for controlling the operation of the stops of a pipe organ, the combination of a plurality of stop members, a push rod engaging each stop member and movable both longitudinally and transverse-

ly, a rod extending transversely of and adjacent to and movable in the direction of the length of said push-rod and adapted by such movement to shift said push rods longitudinally, means for swinging said push rods transversely, means for swinging said transverse rod, and means for effecting the automatically sequent operation of the push-rod swinging means and the transverse-rod swinging means.

5. In mechanism for controlling the operation of the stops of a pipe organ the combination of a plurality of stop members, a push rod for each stop member, a longitudinally shiftable bar for each stop member, each bar carrying a swinging contact piece, means for selectively shifting said bars and selectively swinging the contact pieces borne thereby, and electrically operated means including said contact pieces for shifting said push rods and depressing said stop members.

6. In mechanism for controlling the operation of the stops of a pipe organ, the combination, with a plurality of stop members, a plurality of combination buttons, and a switch movable between alternate setting-up and playing positions, three sets of push rods, one set, characterized as key rods, corresponding in number to the stop members and carrying each a plurality of swinging contact pieces corresponding in number to said combination buttons, the second set of push rods, characterized as combination rods, corresponding in number to said combination buttons, and the third set of push rods, characterized as member-shifting rods corresponding in number to said stop members, an electro-magnet for each push rod and adapted, when energized to swing its own push rod transversely, a rod extending transversely of and movable in the direction of the length of both the key rods and the combination rods, and adapted in such movement to engage and shift longitudinally key rods and combination rods, a rod extending transversely of and movable in the direction of the length of said member-shifting rods, an electro-magnet for each transverse rod and adapted, when energized to swing its own transverse rod, a plurality of swinging contact rods corresponding in number with said combination buttons, an electro-magnet for each contact rod, means operated by one of said combination keys and effective, when the switch stands in setting-up position, for effecting the automatic sequent energizing of the electro-magnets controlling transverse swing of key and combination rods and the electro-magnet controlling the swing of the transverse rod associated therewith, and means operated by one of said

combination keys and effective, when the switch stands in playing position, for effecting the automatic sequent energizing of the electro-magnets for the contact rods, the electro-magnets for the member-moving rods, and the electro-magnet for the transverse rod associated with the member-moving rods.

7. In mechanism for controlling the operation of the stops of a pipe organ, the combination of a plurality of stop members, a plurality of combination buttons, a plurality of longitudinally shiftable and laterally swinging push rods corresponding to the aggregate number of stop members and combination buttons, a rod for each, a rod extending transversely of and movable in the direction of the length of said push-rods and adapted to engage and shift longitudinally said push rods, an electro-magnet for each push rod, the arrangement of push rods being such that the push rods associated with the stop members are drawn by their electro-magnets when energized out of the pathway of the swinging transverse rod and the push rods associated with the combination buttons are drawn by their electro-magnets when energized into said pathway, an electro-magnet for said transverse rod, means for selectively energizing the electro-magnets controlling the swing of push rods associated with the stop members, means for effecting the automatically sequent energizing first of electro-magnets controlling swing of the push rods associated with the combination buttons, and then of the electro-magnet controlling transverse rod swing, and means for moving the stop-members according to the antecedent selective swinging of the push rods associated therewith.

8. In mechanism for controlling the operation of the stops of a pipe organ the combination of a plurality of stop members, a corresponding number of longitudinally shiftable bars bearing each a movable contact piece, a laterally swinging push rod carried by each stop member, means for swinging the push rods selectively, means for selectively shifting said bars through their push rods, according to their individual positions with respect to lateral swing, means for moving the contact piece upon bars segregated by such selective shifting, and means for shifting longitudinally said push-rods, each push-rod-shifting means including an electric circuit completed through a contact piece when moved as aforesaid.

In testimony whereof I have hereunto set my hand.

LEVI M. RINKER.
